POWER OPERATED PRUNING APPARATUS

George W. Magennis, Akron, Ohio

Application November 25, 1938, Serial No. 242,164

3 Claims. (Cl. 30—245)

This invention relates to power operated pruning apparatus, and more especially it relates to hydraulically operated apparatus for operating a cutting instrumentality, such as a shears, that is located relatively remote from the power member.

The chief objects of the invention are to provide a pruning apparatus that may be used with equal facility for pruning relatively high fruit and shade trees and relatively low bushes and shrubs; to provide a mobile apparatus that readily may be moved from place to place; to provide a pruning apparatus that may be operated with but little manual effort; and to provide, in apparatus of the character mentioned, a cutter mounting of readily variable length whereby the apparatus is adapted for pruning near the ground or at substantial elevation above ground. Other objects will be manifest as the description proceeds.

Of the accompanying drawings:

Figure 1 is a plan view of mobile apparatus embodying the invention;

Figure 2 is a fragmentary longitudinal section, on a larger scale, showing the interlock between two units of the extensible cutter mounting;

Figure 3 is a fragmentary longitudinal section, on a larger scale, through the telescoped units of the cutter mounting, at the upper ends thereof, with said units in locked position;

Figure 4 is a longitudinal section through another embodiment of the cutter support; and

Figure 5 is an elevation of another embodiment of the cutter structure such as may be used for cutting light gauge sheet metal and the like.

Referring now to Fig. 1 of the drawings, there is shown a mobile wheeled vehicle or truck 10 upon which the power unit of the apparatus is mounted, said truck being provided with a handle 11 by means of which it may be manually propelled to the desired location for use. Mounted upon the truck 10 is a motor, herein shown as an internal combustion engine 12, said engine being supplied with fuel drawn from a gasoline tank 13 positioned adjacent thereto. For starting the engine 12, a starting pedal 14 is provided, which pedal is operatively connected to starting apparatus (not shown) that has a gear-connection with a gear 15 mounted upon the crank-shaft 16 of the engine 12. Also mounted upon said crank-shaft 16 is driving pulley 17 that is connected by a transmission belt 18 with a driven pulley 19, that latter being mounted upon a shaft 20 that is journaled in a bearing bracket 21. Fixedly mounted upon shaft 20 is a small gear 22 that is

meshed with a larger gear 23 that is mounted upon shaft 24, the latter also being journaled in bearing bracket 21. Also mounted upon shaft 24 is a relatively small gear 25 that is meshed with a relatively large gear 26 that is mounted upon a bushing 27 that is journaled in the bearing bracket 21. Journaled at one end in bushing 27 and at its other end in a bearing bracket 28 is a shaft 29. Slidably keyed upon shaft 29 for movement axially thereof is one element 30 of a jaw clutch, the other element 31 of which is formed on the lateral face of the adjacent hub of gear 26. The clutch elements 30, 31 normally are held apart by means of a compression spring 32 mounted between them upon shaft 29, and a shipper lever 33 engages the clutch element 30 for the purpose of moving said element into clutching engagement with element 31, against the pressure of spring 32. The shipper lever 33 is manually operated by means subsequently to be described. The arrangement is such that the gear 26 is driven whenever the motor 12 is running, but the shaft 29 is rotated only when clutch element 30 operatively is engaged with clutch element 31. The gear reduction between the motor 12 and the gear 26 is such that the latter rotates at 12 to 15 R. P. M.

Between clutch element 30 and bearing bracket 28 the shaft 29 has a cam 35 fixed thereon, which cam operates a pump. Said pump 30 comprises a horizontally arranged cylinder 36 that is carried by a suitable supporting bracket 31, one end of said cylinder being provided with a port 38 for fluid, such as oil or glycerine, contained in said pump. At its other end a piston 39 is slidably mounted in the cylinder, which piston is arranged to be forced forwardly into the cylinder by means of a piston rod 40 that extends into an axial socket 41 formed in the outer end of the piston. The piston rod 40 preferably is of adjustable length, and is slidably mounted for reciprocatory movement in a bearing structure 37a formed on the bracket 31, the end of the piston rod remote from piston 39 being provided with a cam roller 42 that is engageable by cam 35, the latter being shaped so as to force the piston rod toward the piston 39. Connected to the port 38 is a fluid link 43 that extends to the cutting mechanism of the apparatus, said link consisting of flexible tubing, such as rubber reinforced with metal. Mounted in said fluid link is a relief valve 44 having a return connection 45 back to a reserve tank 46 mounted upon the pump, said reserve tank having restricted communication with the pump, as is well understood.

The cutting mechanism of the apparatus comprises a head 47 to which a stationary cutting member 48 is secured by means of bolts 49, 49. Cutting member 48 is formed with an arcuate shearing edge 50, and cooperating with the latter is a movable arcuate blade 51 that is pivotally mounted at 52 upon stationary member 48. If desired the latter may include a short saw 53, and a brush hook 54, both of which may be advantageously employed, upon occasion, during tree and brush pruning operations. The cutting mechanism utilizes the power of the previously described pump for moving the cutter blade 51 into shearing relation with the stationary shearing edge 50, and to this end a fluid pressure operated cylinder 55 is mounted in the head 47, the fluid link 43 from said pump being connected to said cylinder and discharging into an end thereof. Slidably mounted within cylinder 55 is a piston 56, the outer end face of which is formed with a socket 57 in which is received one end of a piston rod 58 the other end of the latter being pivotally connected at 59 to the back of cutter blade 51. A tension spring 60 connected to one of the bolts 49 and to the pivot pin at 59 normally urges the blade 51 to open position, and urges the piston 56 toward the closed end of cylinder 55, there being a cushioning spring 61 positioned between the piston and said closed end of the cylinder. The arrangement is such that pulsation of the fluid in link 43 moves the piston 56 outwardly of its cylinder 55 and thus moves the blade 51 relatively of the cutting edge 50 in a shearing action. The spring 60 restores the blade 51 to open position and forces the fluid in the link 43 back toward the pump.

The cutting mechanism described is portable and is carried at the end of a sectional pole, the sections of which are telescopically arranged, to the end that the effective length of the pole may be selectively varied as desired. As shown, the pole consists of three sections, each of which may be at least three feet in length so that the extended structure will have a length of nine feet at least. The tubular pole-sections are designated 62, 63 and 64, of which the section 62 is of largest diameter, section 63 is of intermediate diameter and fits within section 62, and section 64 is of smallest diameter and fits within section 63. Means being provided for interlocking the sections with each other to maintain them in proper position in the extended condition of the pole.

Pole section 62, which is of largest diameter, constitutes the base or handle portion of the pole. That end of section 62 into which section 63 is fitted is provided interiorly with a tubular sleeve or bushing 66 that is welded or otherwise permanently fixed therein, the lower or inner margin of said bushing being formed with an angular lug or projection 67 that constitutes one element of a bayonet connection. The bushing 66 is of such inside diameter that the pole section 63 has an easy sliding fit therein. Permanently fixed upon the lower end of the section 63, exteriorly thereof and below the bushing 66 of section 62, is a sleeve or bushing 68, the upper margin of which is formed with an undercut slot or recess 69 that constitutes the female element of a bayonet connection. When the bayonet elements 67, 69 are interengaged as shown in Fig. 2, the pole sections 62, 63 are locked in extended relation. The sections readily are collapsed by giving them a slight relative angular movement sufficient to disengage the lug 67 from the recess 69 of bushing 68, after which said sections may be substantially com-

pletely telescoped. In like manner the upper end of section 63 is provided interiorly with a bushing 70 having an angular bayonet lug 71 on the lower margin thereof, and the lower end of section 64 is provided exteriorly with a bushing 72 having a bayonet slot 73 therein, the arrangement being such that the sections 63, 64 may be interlocked in extended position, or telescoped together, in the same manner as sections 62, 63. When the pole sections are in collapsed, telescoped relation it is desirable that they be prevented from turning angularly relatively of each other and to this end the upper end of the section 62 is formed with a pair of diametrically opposed notches or recesses 75, and the upper end of section 63 is provided with a circumscribing collar 76, the under side of which is provided with lugs 77 that are receivable in notches 75 in the collapsed condition of the pole. In like manner the upper face of collar 76 is formed with a pair of notches or recesses 78, and the pole section 64 is provided with a collar 79 formed with lugs 80 that are receivable in said notches 78. The outer end of section 64 is fixed within the cylinder 55 of the cutting apparatus, the collar 79 being mounted upon the section 62 little below said cylinder. The flexible fluid link 43 extends freely through the several pole sections to connect with the cylinder 55, and is readily withdrawn through the lower end of section 62 when the sections are collapsed to shorten the pole.

In order to facilitate the operation of the cutting mechanism, means is provided on the pole for manually causing the pump to operate and thereby to effect operation of the cylinder 55 that controls the cutter blade 51. Said operating means consists of a lever 83 that is pivotally mounted at 84 in a bracket-like fixture 85 that is secured to pole section 62, near the lower end thereof, said lever 83 being arranged to be depressed by the thumb of the operator. Connected to the lever 83 at the opposite end thereof from the thumb-engaging portion, is one end of a flexible cable 86 which cable is slidably encased in a flexible sheath 87. The sheath 87 may be attached to the pole section 62 by clips 88, 88, and may be connected to the fluid link 43 by clips 89. The sheath and cable extend to the truck 10 where they are secured to stationary structures thereon by suitable clips 90, the end of cable 86 being connected to 50 shipper lever 83. The latter has the end thereof remote from clutch member 30 pivotally mounted upon bracket 31 at 91.

In the operation of the apparatus, the motor is put into operation by the starter pedal 14, and continues to run as long as the cutting mechanism is in use. The spring 32 normally keeps the clutch elements 30, 31 in separated position so that the shaft 29 and cam 35 are stationary. When it is desired to operate the cutting mechanism, the operator simply depresses lever 83, which operates shipper lever 83 to move clutch element 30 into driving engagement with driven clutch member 31, thus causing rotation of shaft 29 and cam 35. The latter drives piston rod 40 into the pump and causes the fluid therein to flow toward the cylinder 55 of the cutting mechanism, the piston 56 of the latter being thereby forced outwardly to move the blade 51, against the tension of spring 60, to the cutting position indicated by broken lines in Fig. 1 of the drawings. As soon as continued rotation of the cam 35 releases the pressure upon the piston rod 40, the spring 60 restores the blade 51 to the open position shown in full lines in Fig. 1, with the result that piston 56 is forced back into 75

cylinder 55 and the fluid in the link 43 is forced back toward the pump. The operation described will continue as long as the lever 83 is in depressed condition, at the rate of 12 to 15 operations a minute. The operation of the cutter is the same whether the pole thereof is in extended or collapsed condition.

By means of the apparatus of the invention, pruning operations at high or low elevations may be carried out expeditiously and with little manual effort. The arrangement is such that the pump is operated only when it is desired to operate the cutting mechanism, thereby saving wear upon the pump and fluid link. The apparatus is adapted for all kinds of pruning work, and achieves the other objects set out in the foregoing statement of objects.

Referring now to Fig. 4 of the drawings, there is shown a modified embodiment of the sectional pole upon which the cutting mechanism is mounted. Said pole comprises three sections, namely, 62a, 63a and 64a, which sections are of different diameters so as to interfit one within another. The largest section 62a, which constitutes the base of the pole, has its upper end portion exteriorly threaded at 94, and is provided interiorly with a sleeve 95 that projects somewhat beyond the end of the section, the portion within the section being permanently secured thereto. The inside diameter of the sleeve 95 is such that the pole section 63a has an easy sliding fit therein, and that portion of the sleeve that projects beyond the end of section 62a is exteriorly tapered, as shown at 96, and formed with a circumferential series of longitudinally extending slots 97, 97. Threaded onto portion 94 of section 62a is a cap or gland 98 having an overhanging portion 98a that is interiorly tapered complementary to the taper of sleeve 95, and adapted to engage the slotted tapered portion of the latter to force it radially inwardly in clamping relation with pole section 63a that extends therethrough. The arrangement is such that pole section 62a, 63a may be secured together at an infinite number of positions between fully extended position and fully telescoped position.

In like manner the upper end of pole section 63 is provided interiorly with a sleeve 100 that projects therefrom, the projecting portion being exteriorly tapered and longitudinally slotted. A cap or gland 101 threaded onto the upper end of section 63a has a tapered portion that is engageable with the tapered end portion of sleeve 100 to force the latter inwardly against the pole section 64a that extends therethrough. The cutter body 47 and cylinder 55 are carried upon the upper end of pole section 64a, and the fluid link 43 extends through the tubular pole sections in the same manner as in the previously described embodiment of the invention. The sectional pole shown in Fig. 4, has a greater range of adjustability than that previously described, and the sections are firmly held together in all positions of adjustment. The pole sections are readily separable from each other and one or two sections may be dispensed with in case a short pole is desired, thus lightening the weight of the pole. It will be understood that the poles may comprise more than three sections if desired.

The embodiment of the invention shown in Fig. 5, which is especially adapted for the cutting of light gauge sheet metal, comprises a stationary cutting element 104 that is formed integral with

a shank portion 105, on one end thereof, the other end of said shank portion having a handle 106 secured thereto for convenience of manipulation. Secured to the shank portion 105 is a head 47 that carries a fluid pressure operated cylinder 55 in which is a piston 56, the outer end face of the latter being formed with a socket 57 that receives one end of a piston rod 58. The other end of the latter is pivotally connected at 59 to the back of a movable cutter blade 51, the latter cooperating with the stationary cutter member 104 in a shearing action. The blade 51 is pivotally mounted upon the shank 105 at 52, and a tension spring 60 connecting the pivot 59 to a fixed point on said shank normally urges the blade toward open position. Fluid pressure is conducted to the cylinder 55 through the fluid link 43. Except for the stationary cutter member 104, shank 105 and handle 106, the elements described are identical with those of the previously described embodiment of the invention. The same power apparatus and pump may be employed as in the previously described embodiment. If desired, an operating lever similar to lever 83, may be mounted upon the handle 106, but said lever may be positioned elsewhere for foot-operation if such arrangement is found to be preferable.

Other modification may be resorted to without departing from the spirit of the invention or the scope thereof as defined by the appended claims. 30

What is claimed is:

1. In power operated pruning apparatus comprising a cutter, the combination of a fluid pressure operated cylinder including a piston to which said cutter is connected and operated by reciprocation thereof, means adapted periodically to discharge liquid into said cylinder, yielding means opposing the pressure of said liquid adapted to retract said piston periodically as the liquid pressure is withdrawn, and manually operable means controlling the operation of the liquid-discharging means. 35

2. In lower operated pruning apparatus comprising a cutter, the combination of a portable fluid pressure operated cylinder including a piston to which said cutter is operatively connected, and operated by reciprocation of said piston, a reciprocating pump adapted periodically to discharge liquid into said cylinder, yielding means operatively connected to the piston of said cylinder for periodically forcing liquid from the cylinder back toward the pump, power means for driving the pump, and manually operable means for engaging and disengaging the pump from its driving means. 45

3. In power operated pruning apparatus, the combination of a portable fluid pressure operated cylinder, is fixedly positioned cutter member supported by said cylinder, a movable cutter member cooperating with the aforesaid cutter member and operatively connected to the piston of said cylinder, a reciprocating pump for liquid, a liquid-conducting pipe connecting said cylinder to said pump whereby the latter periodically discharges liquid into said cylinder, yielding means connected to the piston of the cylinder for periodically forcing liquid from the cylinder back to the pump, manually operable means for starting and stopping the pump as a means for controlling operation of the cutter, and a relief valve having connection with said pipe and said pump. 60 65

CERTIFICATE OF CORRECTION.

Patent No. 2,228,635.

January 14, 1941.

GEORGE W. MAGENNIS.

It is hereby certified that error appears in the printed specification of the above numbered patent requiring correction as follows: Page 3, second column, line 57, claim 3, for the word "is" read --a--; and that the said Letters Patent should be read with this correction therein that the same may conform to the record of the case in the Patent Office.

Signed and sealed this 11th day of February, A. D. 1941.

(Seal)

Henry Van Arsdale,
Acting Commissioner of Patents.
